UNITED STATES PATENT OFFICE.

GEORGE A. GIESELER, OF CLEVELAND, OHIO.

DUST-RECOVERING.

1,396,188.

Specification of Letters Patent.

Patented Nov. 8, 1921.

Application filed July 5, 1919. Serial No. 362,726.

To all whom it may concern:

Be it known that I, GEORGE A. GIESELER, a citizen of Germany, residing at Cleveland, in the State of Ohio, have invented certain new and useful Improvements in Dust-Recovering, of which the following is a specification.

My invention relates particularly to that type of apparatus which is used in industrial and other plants to receive dust laden air and extract the dust therefrom. Sometimes such devices are used where the thing of economic importance is the recovery for use of the material carried as a dust by the air. Sometimes the thing of importance is to purify the air so that when it is released into the atmosphere it will not carry with it injurious or harmful material in the form of dust. My invention is equally adapted for either type of apparatus.

20 One embodiment of my invention includes the so called bag filters of the ordinary type. These are generally employed in groups or units so arranged that one group may be put out of operation and cleaned while so inactive. One method of cleaning is to shake the bags of the units so as to detach the collected dust. My invention includes an improved shaking cylinder for this purpose. These devices may be operated by compressed air and the present invention includes a new and improved form of distributing valve or timer by which the compressed air is directed at the proper time to the proper mechanism. As an incident of this operation

35 I provide means for feeding oil to the compressed air with which it is mixed before being distributed to the various parts of the apparatus so that the various parts are lubricated as they are actuated. To avoid fouling the atmosphere and the other machines or structures which may be associated with the filters proper or located near them I provide in the exhaust line for the compressed air a device for removing the oil carried by the air. This is especially advantageous as it prevents the oil laden exhaust air being inhaled by the workmen employed about the plant.

Without intending to limit my invention to the specific details shown I have illustrated one form of apparatus embodying my invention in the accompanying drawings in which Figure 1 is a plan view of the top of two sections of a filter; Fig. 2 is a side elevation of the same; Fig. 3 is a vertical section

through the center of a shaking cylinder for the filter; Fig. 4 is a horizontal section through the exhaust port of the shaking cylinder; Fig. 5 is a longitudinal vertical section through the timer or distributing valve and portions of the mechanism associated therewith; Fig. 6 is a perspective of the timer valve removed from its seat; Figs. 7 and 8 are transverse vertical sections through the timer valve showing it in two different positions; Fig. 9 is a longitudinal vertical section through the oiling mechanism and Fig. 10 is a transverse vertical section through the same.

1 and 2 are filter units of the usual bag type both of which are connected with the air outlet manifold 3. Their connection with the manifold 3 is regulated by means of the usual valve in the housing 4 operated by the usual air cylinders 19, 22 and 29. The usual suction devices may be employed to pull the air through the filters and out through the manifold 3.

A pipe 5 carrying compressed air enters an oil injector 6 provided with a threaded opening 7 to receive any well known type of oil cup 8 which supplies oil to be drawn into the compressed air as it passes through the nozzle 9 which may be removed or adjusted through its screw-threaded connection with the distributing body 10. Oil laden air passes from the oil injector 6 through the pipe 11 to the distributor 12.

The distributor 12 consists of a hollow valve 13 resting in the valve seat 14. The valve 13 and its seat are tapered or inclined so as to fit snugly but not too tightly to rotate. For purposes of illustration this taper is shown in the drawing somewhat exaggerated. The valve seat 14 may be provided with any suitable number of outlet ports, one generally being provided for each unit of filter employed. In the present instance two outlet ports 15 and 16 are shown. The outlet port 15 is connected by means of the pipe 17 to the shaking cylinder 18 and the valve cylinder 19 associated with the filter unit 1. The outlet 16 is connected by means of the pipe 20 to the shaking cylinder 21 and the valve cylinder 22 associated with the filter unit 2. The valve seat 14 is also provided with exhaust ports 23 and 24 which are open to the air. The valve 13 is provided with an air port 25 and with an exhaust groove 26 situated near it and in position to register 110

2
with the ports 15 and 16 after the port 25 has passed from them. Another groove 26 might be similarly situated on the other side of the port 25 so that the grooves would 5 function properly in whichever direction the valve is rotated. Two grooves are shown in Fig. 6 but only one is shown in Figs. 7 and 8. The air port 25 runs entirely through the shell of the valve 13 so as to connect its hollow center with its surface but the groove 26 is merely an indentation in the surface of the valve and does not connect with its hollow interior. The valve 13 is mounted on the shaft 27 which may be rotated by any 10 suitable mechanism 28. As the shaft is rotated the port 25 in the valve 13 comes opposite the outlets 15 and 16 and registers with them in succession.

When the port 25 registers with the outlet 20 port 15 as shown in Fig. 8 the oil laden compressed air introduced through the pipe 11 passes through the pipe 17 and into the cylinder 19 which causes the valve in the housing 4 to close the connection between the manifold 3 and the unit 1. This interrupts 25 the flow of dust laden air through the unit 1 of the filter. At the same time the oil laden compressed air is admitted from the pipe 17 into the shaking cylinder 18 there- 30 by causing it to shake the bags in the unit 1 and free them of the embedded dust as hereinafter explained. As the valve 13 continues to rotate the groove 26 will connect the port 15 with the exhaust port 23 as shown 35 in Fig. 7. This will immediately relieve the pressure in the pipe 17 and thus discontinue the shaking operation of the cylinder 18 and allow the cylinder 19 to let the valve in the housing 4 move so as to again connect 40 the unit 1 with the manifold 3. As the valve 13 further revolves the port 25 comes into register with the port 16 thereby admitting the oil laden air to the shaking cylinder 21 and the valve cylinder 22 of the unit 45 2 so that that unit is disconnected from the manifold and its bags cleaned and then the groove 26 connects the port 16 with the outlet 24 to relieve the pressure and reestablish the working condition of the unit 2. 50 The shaking cylinders 18 and 21 each have a single exhaust port which is connected to a pipe 31 which leads to an oil separator 32. In the present instance I have shown the oil separator 32 of the cyclone 55 type. It will be noted that the oil laden exhaust air does not pass through the separator 32 in a continuous stream but it is intermittent, flowing only when the port 25 in the valve 13 registers with an outlet port 60 in its casing. Since there is a time after each flow when there is no flow through the oil recovering device 32 the entrained oil may flow down from the contact walls and keep them in a relatively clean condition 65 for the next flow of oil laden air. It is thus

possible because of the intermittent flow to obtain at the outlet by the use of a simple separator air substantially free from oil.

The valves in the housing 4 are normally held in position to connect the units to the manifold 3 by means of cylinders 29 which are connected by means of the pipe 30 to the source of oil laden compressed air without passing through the timer 12. These operating cylinders 29 are considerably 75 smaller than the opposing cylinders 19 and 22 so that they may be overcome by the larger cylinders when compressed air is admitted to them. The cylinders 29 preponderate, however, when the supply of compressed air is cut off from the cylinders 19 and 22.

In Figs. 3 and 4 I have shown the type of shaking cylinder which I prefer to use. The compressed air enters from the pipe 17 85 and exhausts from the single exhaust port 33 to which is connected the pipe 31. The usual disk for supporting the filter bags may be attached in any well known way to the shaft 34 which carries the piston 35 90 moving in the cylinder 36. The shaft 34 is surrounded by a coil spring 37 which tends to keep the piston in a raised position. Surrounding the stem 34 and having a longitudinal lost motion thereon is a valve 95 38 which is depressed when the compressed air enters the pipe 17 overcoming the inertia of the spring 37. As the piston 35 travels downward it carries with it the valve 38 which opens the single exhaust port 33 allowing a sudden and immediate release of the air pressure in the cylinder 36 so that the spring 37 may force the piston 35 upward. This moves the valve 38 closing the valve 100 port 33 to allow the accumulation of pressure from the compressed air from the pipe 17 to again force downward the piston 35 thus causing a rapid reciprocation of the shaft 34 and a vigorous shaking of the filter bags connected therewith so long as the port 110 25 of the valve engages the corresponding outlet port in the casing.

I claim as my invention:—

1. In dust recovering apparatus, a plurality of filter units, operating cylinders for 115 each unit, means for mixing oil and compressed air, a hollow tapered valve, means for supplying oil laden compressed air to the hollow of the valve, a port extending through the valve from the hollow to its 120 surface, a casing having a tapered seat for the valve, ports in the casing each connecting with the cylinders of one unit, means for rotating the valve for causing the port in it to register with the ports in the casing 125 in succession, and means for recovering oil from the exhaust air from the cylinders so that the air entering the filters during cleaning may be substantially free from oil.

2. In dust recovering apparatus, a plu- 130

- rality of filter units, a valve operating cylinder and a shaking cylinder for each unit, a single exhaust port for each shaking cylinder, a pipe connecting all the single exhaust 5 ports, an oil separator on the pipe so that the air entering the filters during cleaning may be substantially free from oil; a hollow tapered valve, means for supplying compressed air to the hollow of the valve, a port 10 extending through the valve from the hollow to its surface, a casing having a tapered seat for the valve, ports in the casing each connecting with the cylinders of one unit, and means for rotating the valve for causing 15 the port in it to register with the ports in the casing in succession.
3. In dust recovering apparatus, a plurality of filter units, a valve operating cylinder and a shaking cylinder for each unit, a single exhaust port for each shaking cylinder, a device for distributing compressed air to the cylinders appurtenant each unit in succession, a hollow valve in the device, means for supplying oil laden compressed 20 air to the hollow of the valve, a port extending through the valve from the hollow to its surface, a casing having a tapered seat for the valve, ports in the casing each connecting with the cylinders of one unit, means for rotating the valve for causing the port in it to register with the ports in the casing in succession, and means for recovering oil from the exhaust air from the cylinders so that the air entering the filters during 25 cleaning may be substantially free from oil.
4. In dust recovering apparatus, a filter unit, operating cylinders for the unit, a device for distributing oil laden compressed air to the cylinders, a single exhaust port for 30 each cylinder, and an oil separator on the exhaust so that the air entering the filters during cleaning may be substantially free from oil.
5. In dust recovering apparatus, a plurality of filter units, each having an air outlet valve, a valve operating cylinder and a shaking cylinder for each unit, a single exhaust port for each shaking cylinder to increase the back pressure, and a device for 35 distributing compressed air to the cylinders appurtenant each unit in succession.
6. In dust recovering apparatus, a plu-
- rality of filter units, operating cylinders for each unit, means for feeding oil laden air to the cylinders in succession, and means for recovering oil from the cylinder exhausts so that the air entering the filters during 40 clearing may be substantially free from oil.
7. In dust recovering apparatus, a filter unit, operating cylinders for the unit, a device for admitting oil laden compressed air to the cylinders, means for subsequently relieving the pressure in the cylinders, a single exhaust port for each cylinder, and an oil separator on the exhaust so that the air entering 45 the filters during cleaning may be substantially free from oil.
8. In dust recovering apparatus, a plurality of filter units, a valve operating cylinder and a shaking cylinder for each unit, a single exhaust port for each shaking cylinder, a device for distributing compressed air to the cylinders appurtenant each unit in succession, means for mixing oil and compressed air, a hollow tapered valve in the device, means for supplying oil laden compressed air to the hollow of the valve, a port extending through the valve from the hollow to its surface, a casing having a tapered seat for the valve, ports in the casing each connecting with the cylinders of one unit, means for rotating the valve for causing the port in it to register with the ports in the casing in succession, and means for recovering oil from the exhaust air from 50 the cylinders so that the air entering the filters during cleaning may be substantially free from oil.
9. In dust recovering apparatus, a filter unit, operating means for the unit, means for feeding oil laden air to the operating means, and means for removing oil from the air leaving the operating means so that air entering the filter during cleaning may be substantially free from oil.
10. In dust recovering apparatus, a plurality of filter units, each having an air outlet valve, a valve operating cylinder and a shaking cylinder for each unit, a single exhaust port for each shaking cylinder and a device for distributing compressed air to the cylinders appurtenant each unit in succession.

GEO. A. GIESELER.
